CIRCUIT BREAKER

Gerald J. Freese, Beaver, Pa., assignor to Westinghouse Electric Corporation, East Pittsburgh, Pa., a corporation of Pennsylvania

Application April 29, 1949, Serial No. 90,463

17 Claims. (Cl. 200—116)

1

The invention relates to circuit breakers, and more particularly to manually and automatically operable low voltage circuit breakers for controlling lighting and other moderate power electric circuits.

An object of the invention is to provide an improved circuit breaker having a minimum of parts, that is compact, light in weight and reliable in operation, and inexpensive to manufacture.

Another object of the invention is to provide a circuit breaker embodying an operating mechanism having a small number of parts which are readily assembled and disassembled.

Another object of the invention is to provide a circuit breaker embodying an improved thermal trip means for effecting automatic operation of the breaker.

The novel features that are considered characteristic of the invention are set forth in particular in the appended claims. The invention itself, however, both as to structure and operation, together with additional objects and advantages will be best understood from the following detailed description thereof when read in conjunction with the accompanying drawing.

In said drawing:

Figure 1 is a side elevational view of a circuit breaker, with the cover plate removed, the circuit breaker in the closed position, embodying the principles of the invention.

Fig. 2 is a vertical sectional view taken on line II—II of Fig 1.

Fig. 3 is a side elevational view similar to Fig. 1 but showing the circuit breaker in the manually opened position.

Fig. 4 is a side elevational view of the circuit breaker showing the parts in the tripped open position, and

Fig. 5 is a fragmentary elevational view showing a modification of the invention.

Referring to Figs. 1-4 of the drawing, the circuit breaker comprises in general a two-part separable enclosure of molded insulating material including a housing member 11 and a cover plate 13 therefor, a stationary contact 15, a cooperating movable contact 17 carried by a resilient switch member 19, an operating mechanism indicated generally at 21, a current responsive trip device indicated generally at 23 and a pair of terminals 25 and 27 for connecting the breaker in an electrical circuit.

The resilient switch member 19, at its end opposite the moving contact 17, is given a reverse bend and the formed end 29 is secured as by

rivets 31 as shown or by welding to an arm 33. The arm 33 has ears 35 formed thereon whereby it is pivotally mounted by means of a pin 37 on a bracket 39 secured to the base portion 41 of the housing 11. Between the portion 29 of the switch member 19 and the arm 33 is secured the foot 43 of a current responsive bimetal element 45 formed at right angles to the foot 43 thereof. The free end of the bimetal element 45 is connected by means of a flexible conductor 47 to the terminal 21, thus completing the circuit through the breaker.

The circuit through the breaker extends from the terminal 25 through the stationary contact 15, the movable contact 17, the switch member 19, the bimetal element 43—45 and the flexible conductor 47 to the terminal 21.

The operating mechanism 21 includes an operating lever 49 pivoted on a pin 51 mounted in the side wall of the housing 11. The operating lever has an angular portion 53 at its free end to which is secured a manual operating handle 55 which extends outwardly through an opening 57 in the housing 11. The handle 55 is of molded insulating material and has molded integral therewith an arcuate closure portion 59 for substantially closing the opening 57 in all positions of the handle.

Mounted for rotation on the fixed pin 51 is a cam wheel 61 having a plurality of cam portions 63 formed thereon. In the closed position of the breaker one of the cam portions 63 engages a pin 65 in a formed portion 67 of the switch member 19 to restrain the switch member in closed position.

The switch member 19 is biased open by its inherent resiliency and also by a spring 69 tensioned between the outer end of the operating lever 49 and a pin 71 on the portion 67 of the switch member 19. The pin 65 in the closed position engages the cam portion 63 slightly to the right of the high portion thereof and consequently urges the cam wheel 61 to rotate in a clockwise direction about its pivot 51. Clockwise rotation of the cam wheel 61, however, is normally prevented by the engagement of a cam surface 73 on the adjacent cam portion 63 with a pin 75 on one arm 77 of a three-armed latch member indicated generally at 79. The latch member 79 is pivotally mounted on a pin 81 supported in the side wall of the housing 11. The latch 79 is biased by means of a spring 82 in unlatching direction and is normally restrained in latching position by the engagement of a latch arm 83 thereof with a latch 85 on the free end

of the bimetal element 45. The third arm 37 of the latch member 79 is for the purpose of effecting manual opening of the contacts and resetting the latch following an automatic operation in a manner to be presently described. The cam wheel 61 is provided with a series of laterally projecting pins 89 which are adapted to be engaged by a resilient catch 91 on the operating lever 49 for the purpose of closing the contacts.

The circuit breaker is opened manually by moving the operating handle 55 and thereby the operating lever 49 in a counterclockwise direction from the "on" position (Fig. 1) to the "off" position (Fig. 3). Near the end of the counterclockwise movement the operating lever 49 engages the arm 87 of the latch member 79 and rotates it slightly in a counterclockwise direction. This movement, acting through the arm 77 of the latch member and the pin 75 rotates the cam wheel 61 counterclockwise far enough to move the high point of the cam portion 63 overcenter to the right of the pin 65, whereupon the spring tension of the switch member 19 aided by the spring 69 causes the pin 65 to act on the cam surface 73 and rotate the cam wheel 61 further counterclockwise until the pin 65 rests in one of the low points 93 of the cam wheel. This action takes place quickly under the bias of the springs 19 and 69 as soon as the high point of the cam portion 63 passes by the pin 65, with the result that the contacts are opened with a snap action. A clearance opening 94 (Fig. 2) is provided in the switch member 19 so that the switch member 19 does not strike the cam portion 63 in the open position. The parts have now assumed the positions in which they are shown in Figure 3 with the contacts in the open position.

The circuit breaker is closed by moving the handle 55 clockwise from the "off" position (Fig. 3) to the "on" position (Fig. 1). During this clockwise movement, the catch 91 on the operating lever 49 engages the adjacent pin 89 on the cam wheel 61 and rotates the latter also in a clockwise direction. During the clockwise rotation of the cam wheel 61, the cam surface 73 adjacent the pin 65 acts on the pin to cam the switch member 19 downward to close the contacts. Just as the high point of the cam portion 63 passes to the left of the pin 65, the cam surface 73 next in clockwise direction from the one which just acted on the pin 65 engages the pin 75 on the latch member 79 and is stopped thereby.

It may be observed that the spring 69, in addition to assisting in the opening operation, also holds the operating handle 49—55 in the "on" and the "off" positions. This is due to movement of the spring overcenter across the pivot 51 for the handle when the handle is moved to the "on" or "off" positions.

The circuit breaker is tripped open automatically in response to overload currents by operation of the trip device 23. The bimetal element 45 is heated by overload currents flowing therethrough and, when heated a predetermined amount, deflects toward the left (Fig. 1) and releases the latch member 79. The resilient switch member 19 aided by the spring 69 immediately snaps to the open position. During the opening movement of the switch member 19, the pin 65, acting on a cam surface 85 on the opposite side of the cam portion 63 from the cam surface 73, rotates the cam wheel 61 clockwise until the pin is arrested by engagement thereof with the low point 93 between the adjacent cam

portions 63. Also during the opening movement of the switch member 19 the spring 69 moves over to the left of the pivot 51 for the operating lever, whereupon the operating lever 49 is moved in the direction of the "off" position. The operating handle 55 is arrested in an intermediate "indicating" position by engagement of the operating lever 49 with the arm 37 of the latch member 79 which was moved by its spring 82 to the position shown in Fig. 4 upon its release by the bimetal element.

Before the contacts can be closed following an automatic opening operation, it is necessary to reset and relatch the trip device which is accomplished by moving the handle 55 from the tripped open position (Fig. 4) to the "off" position as shown in Fig. 3. During this movement the operating lever 49 acting on the arm 87 of the latch member 79 rotates the latter counterclockwise to the Figure 3 position, the latch arm 33 wiping by the latch 35 near the end of the resetting movement. The cam wheel 61 does not rotate during the resetting operation since it is held by the spring 69 pressing the pin 65 into the low point 93 between the cam portions 63. During the resetting movement of the operating lever 49, the resilient catch 91 wipes by the pin 89 adjacent thereto and snaps back into alignment with the pin in readiness for a closing operation.

Following reengagement of the latch arm 33 with the latch 35, the contacts are closed in the previously described manner by movement of the handle from the "off" position (Fig. 3) to the "on" position (Fig. 1).

An adjusting screw 97 (Fig. 1) is provided to adjustably vary the tripping point of the breaker. The screw 97 threadedly engages the portion 29 of the switch member, the mounting foot 43 of the bimetal element 45 and the arm 33 adjacent the point where these members are rigidly secured together and adjacent the free end of the arm 33. The rounded head of the screw 97 bears against a concave surface of the base portion 41 of the housing 11. An opening is provided in the base portion 41 to admit a tool whereby the screw 97 may be rotated. Rotation of the screw 97 effects rotation of the arm 33 about the pivot 37 and moves the bimetal element 45 bodily therewith to vary the latch overlap to thereby vary the tripping point of the breaker. Movement of the arm 33 by rotation of the screw 97 also flexes the resilient switch member 19 to vary the contact pressure.

According to the modification shown in Figure 5, means is provided to compensate the thermally responsive trip device for variations in ambient temperatures. The trip device of the modification is mounted in a housing 98 (only a fragment of which is shown) similar to the housing 11 shown in Figs. 1, 3 and 4. A lever 99 (Fig. 5) is pivoted on a pin 101 which is supported in a bracket 103 secured to the bottom portion 105 of the housing 98. A switch member 107 has a mounting foot 109 formed thereon which is secured to the lever 99. Also secured to the lever 99 is the mounting foot 111 of a bimetal element 113, the mounting feet 109 and 111 being rigidly secured to the lever 99 by welding or, as shown, by a rivet 115. The free end of the bimetal element is provided with a latch 117 for cooperation with the latch member 79 and the switch member 107 has a projection 119 carrying a pin 121 for cooperation with the cam wheel 61 (Fig. 1). Secured to the underside of the lever 99 is a tem-

perature responsive, expandable metallic element 123 which is biased by means of a spring 125 into engagement with an adjusting screw 127 threadedly engaging an opening in the base portion 105 of the housing. The spring 125 is compressed between a bracket 129, inserted into and held in place in an angular slot in the base 105, and the free end of the lever 99.

Rotation of the screw 127 in a direction to advance it inwardly will effect upward movement of the lever 99 and thereby increase the overlap of the latch 117 and increase the contact pressure. Turning the screw 127 in the opposite direction permits the spring 125 to move the lever 99 downwardly to decrease the overlap of the latch 117, thus varying the tripping time of the breaker. Backing the screw 127 out also decreases the contact pressure.

The temperature responsive element 123 expands and contracts accordingly as the temperature of the surrounding medium increases and decreases to compensate the tripping bimetal element for changes in ambient temperatures. Upon a rise in ambient temperature the element 123 expands and causes clockwise rotation of the bimetal support lever 99. When the temperature of the surrounding medium decreases, the element 123 contracts permitting the spring 125 to move the lever 99 counterclockwise. In this manner flexing of the tripping bimetal element 113 in response to changes in temperature of the surrounding air is compensated. Thus, the amount of latch overlap remains constant. The temperature responsive element (123) only compensates for the deflection of the bimetal element due to change in ambient temperature.

While the invention has been disclosed in accordance with the provisions of the patent statutes, it is to be understood that various changes in the structural details thereof may be made without departing from some of the essential features of the invention.

I claim as my invention:

1. A circuit breaker comprising stationary and movable contact means, a resilient switch member biased open and carrying said movable contact means, a rotatable member having a plurality of radial cam portions thereon, one of said radial cam portions normally engaging said switch member to maintain said switch member closed against its normal bias, a latch member having a portion engaging another of said radial cam portions to releasably restrain said rotatable member, a trip device operable to release said latch member and permit said biased switch member to rotate said rotatable member in one direction to effect automatic opening movement of said switch member, and manual means movable between "off" and "on" positions and operable when moved from said "off" position to said "on" position to engage and rotate said rotatable member in said one direction to cause a third radial cam portion to engage and cam said switch member to closed position.

2. A circuit breaker comprising stationary and movable contact means, a switch member carrying said movable contact and biased in opening direction, a rotatable member having a plurality of radially extending portions thereon, one of said radial portions normally engaging and restraining said switch member in closed position against its normal bias, restraining means engaging another of said radial portions to releasably restrain said rotatable member, and a current responsive trip device operable in response

to overload currents to release said restraining means to permit said biased switch member to rotate said rotatable member and effect automatic opening movement of said switch member.

3. A circuit breaker comprising stationary and movable contact means, a switch member carrying said movable contact and biased in opening direction, a rotatable member having a plurality of radial cam portions thereon, one of said radial cam portions normally restraining said switch member in closed position against its bias, restraining means engaging another of said radial cam portions to releasably restrain said rotatable member, a current responsive trip device operable in response to overload currents to release said restraining means to permit the bias of said switch member to rotate said rotatable member and effect automatic opening movement of said switch member, and manual means operable to engage and rotate said rotatable member in said one direction to cause one of said radial cam portions to engage and move said switch member to closed position.

4. A circuit breaker comprising a switch member movable to open and close the circuit, biasing means biasing said switch member in opening direction, a rotatable cam member having a plurality of radially extending cam portions thereon, one of said cam portions normally holding said switch member in closed position, a pivot for said cam member, restraining means cooperating with another of said radio cam portions to releasably restrain said cam member in position to hold said switch member closed, trip means restraining said restraining means operable to release said restraining means to effect automatic opening movement of said switch member, and manual means pivoted on said pivot and movable in one direction to engage and actuate said restraining means to cause said restraining means to rotate said cam member in one direction to permit said biasing means to move said switch member in opening direction, said manual means being movable in another direction to engage and rotate said cam member in another direction to cause said cam member to move said switch member to closed position.

5. A circuit breaker comprising separable contacts, a switch member movable to open and close said contacts, a pivoted lever supporting said switch member, biasing means biasing said switch member in opening direction, a rotatable cam member normally engaging and holding said switch member in closed position, said biasing means also biasing said cam member for rotation in one direction to permit opening movement of said switch member, a releasable member normally restraining said rotatable cam member against rotation, trip means mounted on said pivoted lever for restraining said releasable member, said trip means being operable to release said releasable member and effect automatic opening movement of said switch member, and adjusting means for adjusting said pivoted lever to thereby vary the tripping time of the breaker.

6. A circuit breaker comprising separable contacts, a switch member movable to open and close said contacts, a pivoted lever supporting said switch member, biasing means biasing said switch member in opening direction, a rotatable cam member normally engaging and holding said switch member in closed position, said biasing means also biasing said cam member for rotation in one direction to permit opening move-

ment of said switch member, a releasable member normally restraining said rotatable cam member against rotation, trip means mounted on said pivoted lever for restraining said releasable member, said trip means being operable to release said releasable member and effect automatic opening movement of said switch member, adjusting means for adjusting said pivoted lever to thereby vary the tripping time of the breaker, and a thermally responsive element disposed between said pivoted lever and said adjusting means for compensating said trip means for changes in ambient temperatures.

7. A circuit breaker comprising relatively movable contact means, a resilient switch member movable to open and close said contact means, operating means operable to effect automatic opening movement of said switch member, a thermally responsive element heated by the current of the circuit and operable when heated a predetermined amount to effect operation of said operating means, a movable lever mounting both said switch member and said thermally responsive element, and adjusting means for moving said lever to vary the tripping time of the breaker.

8. A circuit breaker comprising separable contact means, a switch member movable to open and close said contact means, releasable operating means for actuating said switch member, a bimetal element heated by the current of the circuit and operable when heated a predetermined amount to release said operating means and effect automatic opening of said contact means, a movable lever upon which said switch member and said bimetal element are mounted, adjusting means for moving said lever to vary the tripping time of the breaker, and a temperature responsive element attached to said pivoted lever and disposed between said lever and said adjusting means for compensating said bimetal element for changes in ambient temperatures.

9. A circuit breaker comprising separable contact means, a resilient switch member movable to open and close said contact means, operating means for actuating said switch member, a bimetal element responsive to overload currents to effect operation of said operating means and automatic opening of said contact means, a movable lever upon one side of which said switch member and said bimetal element are mounted, adjusting means for moving said lever to simultaneously vary the contact pressure and the tripping time of the breaker, a temperature responsive element mounted on the other side of said lever and disposed between said lever and said adjusting means for compensating said bimetal element for changes in ambient temperature, and resilient means for maintaining said temperature responsive element in engagement with said adjusting means.

10. A circuit breaker comprising relatively movable contact means, a switch member biased in opening direction and movable to open and close said contact means, a rotatable member having cam means thereon engaging said switch member to hold said switch member in closed position against its bias, manual means for engaging and rotating said rotatable member in one direction to disengage said cam means from said switch member and permit opening movement of said switch member, and trip means operable in response to overload currents for effecting rotation of said rotatable member in the opposite direction to disengage said cam means

from said switch member and effect automatic opening movement of said switch member.

11. A circuit breaker comprising relatively movable contact means, a switch member movable to open and close said contact means, means biasing said switch member in opening direction, a rotatable cam member having a plurality of cam projections thereon, one of said cam projections normally engaging said switch member to hold said switch member in closed position, said biasing means normally biasing said cam member for rotation in one direction, a releasable member releasably restraining said cam member against rotation in said one direction, trip means operable to release said releasable means to permit said biasing means to rotate said cam member in said one direction and to move said switch member to open position, and manual means engageable with said cam member for rotating said cam member in said one direction to engage the succeeding cam projection with said switch member and move said switch member to closed position.

12. A circuit breaker comprising relatively movable contact means biased open, a rotatable cam member having a plurality of cam projections spaced about the periphery thereof, one of said cam projections normally engaging said movable contact means to hold said contact means closed, said cam member being rotatable step by step in one direction to first disengage said one cam projection from said contact means and effect automatic opening of said contact means and then engage the succeeding cam projection with said contact means to effect closing of said contact means, trip means operable to effect rotation of said cam member one step to effect automatic opening of said contact means, and manual means operable to engage said cam member and effect rotation of said cam member another step to close said contact means.

13. A circuit breaker comprising relatively movable contact means biased open, a rotatable cam member having a plurality of cam projections spaced about the periphery thereof, one of said cam projections normally engaging said contact means to hold said contact means closed, said cam member being rotatable step by step in one direction to first disengage said one cam projection from said contact means and effect automatic opening of said contact means and then engage the succeeding cam projection with said contact means to effect closing of said contact means, trip means operable to effect rotation of said cam member one step to effect automatic opening of said contact means, and manual means operable to engage said cam member and effect rotation of said cam member another step to close said contact means, said cam member advancing one cam projection for each automatic opening and subsequent closing operation.

14. A circuit breaker comprising relatively movable contact means, a resilient switch member movable to open and close said contact means, operating means operable to effect automatic opening movement of said switch member, a thermally responsive element disposed in electrical engagement with said switch arm, said thermally responsive element being heated by the current of the circuit and operable when heated a predetermined amount to effect an operation of said operating means, a movable lever mounting both said switch arm and said thermally responsive element, and adjusting means for moving

said lever to vary the tripping time of said breaker.

15. A circuit breaker comprising stationary and movable contact means, a switch member carrying said movable contact means and biased to open position, a rotatable member having a plurality of radially extending projections thereon, one of said radial projections normally engaging said switch member to maintain said switch member closed against its bias, a latch member having a portion engaging another of said radial projections to releasably restrain said rotatable member, and a trip device operable to release said latch member and permit said biased switch member to rotate said rotatable member to disengage said one radial projection from said switch member to effect automatic opening movement of said switch member.

16. A circuit breaker comprising stationary and movable contact means, a switch member carrying said movable contact means and biased in opening direction, a cam member rotatable about a pivot normally engaging and restraining said switch member in closed position against its bias, a releasable member normally engaging and restraining said cam member, means releasably restraining said releasable member in restraining position, manual means movable in one direction to engage and actuate said releasable member to cause said releasable member to rotate said cam member in one direction to permit opening movement of said switch member, and said manual means being movable in another direction to engage and rotate said cam member in another direction to cause said cam member to move said switch member to closed position.

17. A circuit breaker comprising a switch member movable to open and close the circuit, means biasing said switch member in opening direction, a rotatable cam member having a plurality of radially extending cam portions thereon, one of said radial cam portions being normally in a position to engage and restrain said switch member in closed position, said biasing means normally biasing said cam member for rotation in one direction, a releasable member engaging another one of said radial cam portions to restrain said cam member in said restraining position, a trip device normally restraining said releasable member and operable in response to overload currents to release said releasable member to permit said biasing means to rotate said cam member in said one direction and to move said switch member to open position, and manual means movable in one direction to engage and reset said releasable member and operable when moved in another direction to engage and advance said cam member to cause the succeeding radial cam portion to engage and move said switch member to closed position.
